(57) **CLAIM**

The ornamental design for a quad small form-factor pluggable extraction latch design for AOC, as shown and described.

DESCRIPTION

FIG. 1 is a top perspective view of a quad small form-factor pluggable extraction latch design for AOC, showing my new design;

FIG. 2 is an enlarged view of area 2 in FIG. 1 thereof;

FIG. 3 is a side elevation view thereof;

FIG. 4 is a top elevation view thereof;

FIG. 5 is an enlarged view of area 5 in FIG. 4 thereof;

FIG. 6 is a top perspective view of the environment thereof;

FIG. 7 is a side elevation view of the environment thereof;

FIG. 8 is a top elevation view of the environment thereof; and,

FIG. 9 is a top elevation of the quad small form-factor pluggable extraction latch design for AOC thereof, in use condition with environment.

The broken lines in the drawing views is for illustration unclaimed environment only, and forms no parts of the claimed design.

The wordings and the logo shown in FIGS. 1, 3 and 7 forming part of the claimed design, are registered trademarks owned by Mellanox Technologies, Inc.
